1 Sheet Drawing. 13 Pages Specification

A print-out image-forming layer on an easily cut and stripped adhesive backed support may be used on the back side of a relief printing plate to provide a makeready means for adjusting pressure on printing areas of a printing plate. A method for forming the makeready comprises coating a light-sensitive, preferably print-out, composition in a film-forming vehicle on one side of a support and an adhesive on the opposite side, adhering the adhesive side of the support to the back side of a printing plate, exposing the light-sensitive composition in register with the printing plate relief image and utilizing the image in the sensitive composition as a guide for removal of the film from non-image areas.
